UNITED STATES PATENT OFFICE

164,993

STERILIZER FOR TELEPHONE MOUTHPIECE

David G. Jack, Houston, Tex.

Application January 19, 1950, Serial No. 7,350

Term of patent 7 years

(Cl. D26—14)

To all whom it may concern:

Be it known that I, David Gardner Jack, a citizen of the United States, residing at Houston, in the county of Harris and State of Texas, have invented a new, original, and ornamental Design for a Sterilizer for Telephone Mouthpiece, of which the following is a specification, reference being had to the accompanying drawing, forming part thereof.

In the drawings:

Figure #1 is a top plan view looking at the top of the sterilizer for telephone mouthpiece, showing my new design.

Figure #2 is a side elevational view in the closed position.

Figure #3 is a plan view looking at the bottom.

Figure #4 is a front elevational view.

Figure #5 is a rear elevational view thereof.

I claim:

The ornamental design for a sterilizer for telephone mouthpiece, as shown.

DAVID G. JACK.
